(57) **CLAIM**

The ornamental design for a nesting block set, as shown and described.

DESCRIPTION

FIG. 1 is a top, front perspective view showing our new design for a nesting block set in its nested configuration;

FIG. 2 is a bottom, front perspective view thereof;

FIG. 3 is a front view thereof, the rear view being a mirror image thereof;

FIG. 4 is a right side view thereof, the left side view being a mirror image thereof;

FIG. 5 is a top view thereof;

FIG. 6 is a bottom view thereof;

FIG. 7 is a top and front perspective view showing the design in its stacked configuration;

FIG. 8 is a bottom, front perspective view thereof;

FIG. 9 is a front view thereof, the rear view being a mirror image thereof;

FIG. 10 is a right side view thereof, the left side view being a mirror image thereof;

FIG. 11 is a top view thereof; and,

FIG. 12 is a bottom view thereof.

The broken lines are included for the purpose of illustrating seam lines and components of the nesting block set that form no part of the claimed design.

1 Claim, 12 Drawing Sheets
